(57) **CLAIM**

The ornamental design for a flexible bushing, or the like, as shown and described.

DESCRIPTION

FIG. 1 is a perspective view of the invented flexible bushing or the like showing the new design;

FIG. 2 is a bottom view thereof;

FIG. 3 is a front view thereof;

FIG. 4 is a top view thereof;

FIG. 5 is a rear view thereof;

FIG. 6 is a left end thereof; and

FIG. 7 is a right end view thereof.

FIG. 8 is a perspective view of an alternative embodiment of the new design for a flexible bushing.

FIG. 9 is a top view thereof;

FIG. 10 is a front view thereof;

FIG. 11 is a bottom view thereof;

FIG. 12 is a rear view thereof.

FIG. 13 is a left end thereof; and

FIG. 14 is a right end view thereof; and,

FIG. 15 is a perspective view of the invented flexible bushing of FIG. 8 installed about a shaft. The other embodiment is installed in a similar manner.

Material in dotted lines shows the environment in which the invented design is used, and forms no part of the invented design.
